Attorney.

UNITED STATES PATENT OFFICE.

ELWOOD F. HESCH, OF NEWPORT, KENTUCKY.

COASTER VEHICLE.

Application filed August 27, 1926. Serial No. 132,025.

My invention relates to coaster vehicles and has particular reference to the vehicle of the so-called scooter type arranged with runners for operation on ice or snow.

The principal object of the present invention is to provide a coaster vehicle adapted for operation over snow and ice, in which suitable braking mechanism is provided.

Further objects of the invention will appear from the following detailed description thereof.

In the drawings:

Figure 1 is a plan view of the device.

Figure 2 is a front elevation of the front runner.

Figure 3 is a side elevation of said runner.

Figure 4 is a side elevation of the device parts being shown in section.

The numeral 1 indicates the body of the coaster, the same comprising a flat board upon which the operator may either sit or stand. Secured near the front end of the board 1 is a sleeve or bushing 2. Mounted

on the underside of the body 1, below the bushing 2 is a flange bearing plate 3, rotatably mounted in which is a bearing 4, said bearing constituting a round or disc-shaped plate adapted to fit snugly inside the bearing plate 3. The bearing 4 has an aperture

5 which registers with the aperture of the bushing 2. Pivotedly mounted on a pin 6 in the bearing 4 is a shaft 7, the upper end of which is provided with a handle 8. Se-

cured to the lower end of the shaft 7 is the steering runner 9 shown in detail in Figures 2 and 3. The runner 9 comprises a substantially hull-shaped body 10 with a front central rib 11 which extends down-

wardly under the front portion of the body 10 as shown in Figures 3 and 4, said front portion inclining upwardly as indicated.

The central under-portion of the body 10 is flat and serves as a runner proper while the

rib 11 serves for steering. The rear portion of the base of the body 10 inclines upwardly as shown in Figures 3 and 4, and there is bolted or riveted thereto a plate 12 having calks or teeth 13 which serve for

50 braking or stopping the device as herein-after mentioned. The front wall of the aperture in the bearing inclines inwardly from the bottom of the plate up so that the upper edge 14 is arranged to abut against the front portion of the shaft 7 above the pin 6 for

55 the purpose hereinafter mentioned. Rigidly

secured to the rear portion of the body 1 of the device are runners 15.

The shaft 7 is provided with a rod 16 pivotally secured at 17 thereto, said rod 60 serving as a means for pulling the device. A clip 18 is provided to hold the rod 16 in upright position against the shaft 7 when it is not required for use.

The operation of the device will be apparent from the foregoing description. The operator may steer the device by rotating the shaft which turns the front runner 9, the bearing 4 rotating in the bearing plate 3. The aperture in the bushing 2 as well 70 as that in the bearing plate are sufficiently large to permit the tilting of the upper portion of the shaft backwardly which will bring the calks 13 on the rear of the front runner downwardly so as to take hold in the 75 ice or snow for the purpose of slowing the device or stopping the same. By reason of the abutment of the edge 14 against the shaft 7 above the pin 6, the front runner is prevented from tilting forwardly when it 80 strikes an obstruction, as will be obvious.

It will be understood that certain modifications may be made in the details of construction above set forth and shown in the drawings without departing from the spirit and 85 scope of my invention as defined in the appended claims.

Having thus fully described my invention, what I claim as new and desire to secure by Letters Patent is:

1. A coaster vehicle, comprising in combination with a body and a rear runner, a steering runner, means for mounting said steering runner so that the same will tilt along its axis, a plate removably mounted on 95 the rear portion of said steering runner, and calks on said plate arranged to engage in the surface over which the runner is operating.

2. A coaster vehicle, comprising in combination with a body and a rear runner, a steering runner, means for mounting said steering runner so that the same will tilt along its axis, calks on the rear portion of said runner arranged to engage in the surface over which the runner is operating, and means for preventing said steering runner from tilting forward.

3. A coaster vehicle, comprising in combination with a body and a rear runner, a steering runner, means for mounting said steering runner so that the same will tilt

2
along its axis, a plate removably mounted on the rear portion of said steering runner, calks on said plate arranged to engage in the surface over which the runner is operating, and means for preventing said steering runner from tilting forward.

4. A coaster vehicle, comprising in combination with a body and rear runner, a shaft, a rotatable mounting in the front part 10 of said body for said shaft, said shaft being pivotally secured in said mounting, a steering runner on the lower end of said shaft, and calks on the rear portion of said runner arranged to engage in the surface over which the runner is operating when said 15 shaft is tilted on its pivotal mounting.

5. A coaster vehicle, comprising in combination with a body and rear runner, a shaft, a rotatable mounting in the front part 20 of said body for said shaft, said shaft being pivotally secured in said mounting, a steering runner on the lower end of said shaft, a plate removably mounted on the rear portion of said steering runner, and calks on 25 said plate arranged to engage in the surface over which the runner is operating.

6. A coaster vehicle, comprising in combination with a body and rear runner, a shaft, a rotatable mounting in the front part of said body for said shaft, said shaft being 30 pivotally secured in said mounting, a steering runner on the lower end of said shaft, calks on the rear portion of said runner arranged to engage in the surface over which the runner is operating when said shaft is 35 tilted on its pivotal mounting, and means for preventing said steering runner from tilting forward.

7. A coaster vehicle, comprising in combination with a body and rear runner, a shaft, a rotatable mounting in the front part of said body for said shaft, said shaft being 40 pivotally secured in said mounting, a steering runner on the lower end of said shaft, a plate removably mounted on the rear 45 portion of said steering runner, calks on said plate arranged to engage in the surface over which the runner is operating, and means for preventing said steering runner from tilting forward.

ELWOOD F. HESCH.
